225,556

COMBINED MULTI-UNIT DISH SET AND TRAY HOLDER THEREFOR

Steven J. Cyr and Mark W. Whelan, Chippewa Falls,
Wis., assignors to Standard Oil Company, Chicago,
Ill.

Filed Dec. 16, 1970, Ser. No. 26,523

Term of patent 14 years

Int. Cl. D7—01

U.S. Cl. D44—10

Fig. 1

Fig. 2

FIG. 1 is a perspective view of a combined multi-unit dish set and tray holder therefor showing our new design:

FIG. 2 is a top plan view;

FIG. 3 is a bottom plan view;

FIG. 4 is a front elevational view;

FIG. 5 is a side elevational view; and

FIG. 6 is a cross-sectional front elevational view taken along the line 6-6 of FIG. 2.

We claim:

The ornamental design for a combined multi-unit dish set and tray holder therefor, as shown.
